UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

SUPPORT FOR ELECTRIC CONDUCTORS.

Application filed November 23, 1922. Serial No. 602,907.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Sup-
ports for Electric Conductors, of which the
following is a specification.

My invention relates to overhead support-
10 ing devices for conductors and relates par-
ticularly to that class of devices known as
insulated crossings in which two conductors
may cross each other and maintained in in-
sulated relation to each other.

15 My invention has for its object a device
whereby a maximum amount of insulation
may be secured between the conductors
which cross each other and in adjacent rela-
tion to each other.

20 A device whereby two conductors crossing
each other may be held together in fixed
and insulated relation to each other is old
in the art, but in devices of this character
thus far known to the applicant, the insula-
25 tion between the two conductors is usually
of wood, fibre, etc., and is not sufficient, es-
pecially where the two conductors are of
opposite polarity or the potential between
them is reasonably high, without making
30 the device large and clumsy which is a detri-
ment in an overhead support of this kind
on account of the weight to be suspended.
With my invention I am able to maintain
as light a construction as mechanical re-
35 quirements will permit and increase to a
very large degree the insulating factor be-
tween the two conductors, and this I bring
about by introducing into the path between
the conductors air insulation which is much
40 more effective than wood, fibre, etc., as an
insulator. At the same time the mechanical
strength of the device embodying my in-
vention is maintained nearly as great as in
a construction in which my invention is
45 not involved. The mechanical strength,
however, may be fully secured by a very
slight increase in the weight, but such in-
crease in weight is very low compared to
the increase of the insulation resistance
50 which may be secured by incorporating my
invention, whereby the leakage path over the
surface of the wood or fibre between the
conductors or the metallic attachments se-
cured thereto is greatly increased.

55 My invention resides in the new and novel

combination, construction and relation of
the various parts hereinafter fully described
and shown in the drawings.

In the accompanying drawing:

Figure 1 shows a side view in elevation of
an insulator in which my invention is em-
bodied.

Fig. 2 shows a top plan view of Fig. 1.

Fig. 3 shows a view in section of Fig. 2
65 taken on the line 3—3.

In my preferred construction I employ
a member 1 of insulating material which
may be of wood, fibre, or other suitable in-
sulating substance and having the proper
mechanical strength. To each end of the
70 member 1 is secured a metal end member
2. These members are shown as secured
to the member 1 by means of bolts and nuts
3. Each end member 2 is provided with a
clamping means 4 whereby the conductor 5
75 may be securely held in place in the end
members 2. To the lower edge of the mem-
ber 1 are narrow members 6—6 of insulating
material which acts as a guide for a part
of the distance of a current collector passing
80 across the device in contact with the under-
side. Secured to the underside of the mem-
ber 1 and intermediate the members 6—6 is
a metallic pan 7 secured to the member 1 by
means of the bolts and nuts 8 and which
85 guides the current collector across the space
between the members 6—6 and provided
with projecting arms 9 to which the con-
ductor 10 is secured. It will be noted that
the conductors 5 and 10 are continuous and
also that the pan 7 is shown as fixed with
90 respect to the member 1 although the pan
may be arranged to swivel about its center
so as to increase or decrease the angle A if
desired. This latter construction is old and
well known in the art and forms no part of
95 my invention. The pan 7 and arms 9 act
as a guide for the current collector passing
underneath the device along the conductor
10 and in contact with the lower surface of
the device, and the pan 7 also permits the
100 current collector to cross in the center of
the device in passing along the conductor
5, the whole device constituting what is com-
monly known in the art as a trolley wire
105 crossing and in the construction thus far
described there is no claim for any new and
novel features.

The member 1 is provided along its top
edge with a longitudinal groove 12 in which
110

rests the conductor 5 and its lower edge is provided with a transverse groove 13 to receive the conductor 10. It is quite obvious that the groove 12 can be eliminated and the conductor 5 rest upon the upper edge of the member 1.

It has been found in devices of this class that the insulation between the conductors 5 and 10 is not sufficient to meet the requirements where the voltage between these wires is 500 or greater as the distance over the surface of the member 1 from the conductor 5 to any part of the pan 7 is not sufficient to prevent leakage of the electric current, and this is especially true in wet or damp weather. This leakage current is sufficient to char or carbonize the surface of the insulating member 1 if the same is formed of wood or other fibrous material and, therefore, to increase the insulating resistance between the conductor 5 and the conductor 10 or the pan 7, I introduce air resistance therebetween by means of the slot 14. This slot is shown in Fig. 3 as extending entirely through the member 1 in a transverse direction and for a considerable distance in a longitudinal direction. The extent of the slot in the longitudinal direction depends upon the length of the pan member 7 or other metallic parts which may be in electrical engagement with the conductor 10. It will be noted in Fig. 1 that if the slot 14 were not present the leakage distance would be across the surface of the member 1 from the conductor 5 to the lug 15 as indicated by the line B, but by observing the relation of parts in Figs. 1 and 3 it will be noted that with the slot 14 the insulation resistance between the conductor 5 and the lugs 15 has been increased enormously. It will also be observed that the surface insulation between the conductor 5 and any other part of the pan has been very greatly increased, or between the conductor 5 and the conductor 10, and this increase is dependent upon the length of the slot 14. At the same time the mechanical strength of the member 1 has not been materially effected as the slot 14 need not be very wide. The nearer the slot is placed to the neutral axis the less the mechanical strength of the member 1 will be affected, at the same time not decreasing the insulating properties secured by the slot 14.

The upper edge of the member, immediately below the conductor 5, might be cut out thereby interposing air resistance between the conductor 5 and the member 1 immediately below, and while this comes within the scope of my invention, it would reduce the mechanical strength of the insulating member 1 materially, as in that case material would be removed which is farthest from the neutral axis and which, therefore, is of the greatest benefit to the mechanical strength of the member 1, but, as already

explained, by interposing a slot 14 between the two conductors as shown, which is my preferred construction, and placing this slot as near the neutral axis as possible, very little material has been removed which offers strength to the member 1 and all of the material above the slot 14 acts in compression and all of the material below the slot acts in tension.

There are no doubt modifications of my invention which will be evident to those skilled in the art, therefore, I do not wish to be limited other than by my claims.

I claim:—

1. The combination of an elongated insulating member, means to secure a conductor to each end of the member permitting the conductor to pass along one edge in longitudinal relation thereto, means to secure a conductor to an opposite edge in transverse relation thereto and an elongated slot extending through said member and substantially along its longitudinal neutral axis between said conductors. 80

2. The combination of a pair of conductors spaced apart and transversely disposed to each other and means secured to said conductors for maintaining them in separated and electrically insulated relation to each other, said means comprising two solid electrical insulators and one air insulation in series in the direct path between the conductors. 90

3. The combination with a cross-over comprising an insulating member to receive a conductor along one edge in longitudinal relation thereto and a conductor along an opposite edge in transverse relation thereto and means to secure said conductors to such member, of an elongated slot through said members between said conductors to increase the electrical resistance between said conductors by the air medium within said slot. 100

4. In a cross-over provided with an insulating member adapted to receive a conductor along its upper edge in longitudinal relation thereto and a conductor along its opposite edge in transverse relation thereto, the combination therewith of means interposed between the upper and lower edges of the member to increase the electrical resistance thereof by a medium of air. 110

5. In a cross-over provided with an insulating member adapted to receive a conductor along one edge in longitudinal relation thereto and a conductor along the opposite edge in transverse relation thereto, the combination therewith of means interposed between said conductors and incorporated with said member of greater electrical resistance than that of said member. 120

6. In a cross-over adapted to receive a pair of conductors in crossed relation and insulated from each other by an insulating member, the combination therewith of means for 130

incorporating in said member air resistance to increase the resistance between said conductors.

7. In a cross-over adapted to receive a pair of conductors in crossed relation and insulated from each other by means of an insulating member, the combination therewith of means incorporated in said member to increase the insulation thereof between said conductors.

8. An insulated cross-over for a pair of conductors having a difference of potential comprising an insulating member, means at each end of the insulating member to secure one of the conductors thereto and permit the conductor to pass along the upper edge of the insulating member, means secured to the insulating member to secure the other conductor thereto and a slot in the insulating member interposed between the two conductors to increase the resistance therebetween in excess of that provided by the insulating member.

9. An insulated cross-over for a pair of conductors having a difference of potential comprising an insulating member, means at each end of the insulating member to secure one of the conductors thereto and permit the conductor to pass along the upper surface of the insulating member, means secured to the insulating member to receive the other conductor and means interposed between the two conductors to increase the insulation between the conductors in excess of that provided by the insulating member.

10. An insulated cross-over comprising an elongated insulating member, means secured to each end of the member to receive a conductor and permit the conductor to pass along one edge of the member in longitudinal relation thereto, means to secure a conductor to the opposite edge in transverse relation thereto and an elongated slot through the member intermediate the conductors and extending a distance in both directions along the member from the transverse conductor.

11. An insulated cross-over comprising an elongated insulating member, means secured to each end of the member to receive a conductor and permit the conductor to pass along one edge of the member in a longi-

tudinal direction, means to secure a second conductor to the opposite edge of the member and in transverse relation thereto, and means to introduce an air space in series with the member to increase the electrical resistance of the path between the conductors.

12. An insulated cross-over comprising an elongated insulating member, means secured to each end of the member to receive a conductor and permit the conductor to pass along one edge of the member in a longitudinal direction, means to secure a second conductor to the opposite edge of the member and means for increasing the length of the leakage path across the surface of the member between the first conductor and the holding means for the second conductor.

13. An insulated conductor cross-over comprising an insulating member and a plurality of conductors secured thereto in insulated relation having in combination therewith means for increasing the electrical resistance between the conductors without increasing the weight of the parts.

14. An insulated conductor cross-over comprising an insulating member and a plurality of conductors secured thereto in insulated relation and means for introducing in combination therewith air insulation to increase the electrical resistance between the conductors.

15. An insulated conductor cross-over comprising an insulating member and a plurality of conductors secured thereto in insulated relation and having in combination therewith means for increasing the electrical resistance between the wires, both through and over the surface of the insulating member, without changing the over all dimensions of the insulating member.

16. An insulated conductor cross-over comprising an insulating member and a plurality of conductors secured thereto in insulated relation, having in combination therewith means for increasing the electrical resistance path between the conductors without increasing the distance between the conductors.

In testimony whereof I affix my signature.
SAMUEL S. MATTHES.
